(57) **CLAIM**

The ornamental design for a writing instrument, as shown and described.

DESCRIPTION

FIG. 1 is a front elevational view of a writing instrument according to the present invention;

FIG. 2 is a right side elevational view of the writing instrument of FIG. 1, the left side being a mirror image of the right side;

FIG. 3 is a rear elevational view of the writing instrument of FIG. 1;

FIG. 4 is a top plan view of the writing instrument of FIG. 1;

FIG. 5 is a bottom plan view of the writing instrument of FIG. 1;

FIG. 6 is a top, right side perspective view of the writing instrument of FIG. 1, with a writing medium thereof being projected outward;

FIG. 7 is a sectional view along the line 7—7 of the writing instrument of FIG. 1;

FIG. 8 is a sectional view along the line 8—8 of the writing instrument of FIG. 1; and,

FIG. 9 is a sectional view along the line 9—9 of the writing instrument of FIG. 1.
